United States Patent Office

Des. 184,781
Patented Mar. 31, 1959

184,781

COMBINATION DISPLAY, TRANSPORTING AND SERVING CART FOR FOODS

Lyle C. Todd, Wichita, Kans., assignor to Wichita Precision Tool Company, Inc., Wichita, Kans., a corporation of Kansas

Application June 30, 1958, Serial No. 51,603

Term of patent 3½ years

(Cl. D14—3)

Fig. 1.

Fig. 2.

Fig. 1 is a perspective view showing the top, side and one end of the combination display, transporting and serving cart for foods, showing my new design.

Fig. 2 is a perspective view showing the top, opposite side and opposite end of the same.

I claim:

The ornamental design for a combination display, transporting and serving cart for foods, substantially as shown.
